UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 12,976, dated June 13, 1882.

Application filed May 1, 1882. Term of patent 3½ years.

To all whom it may concern:

Be it known that I, DAVID G. MELVILLE, of Medford, in the county of Middlesex and State of Massachusetts, have invented a new and 5 original Design for Carpets, of which the following is a specification.

The nature of my design is shown in the accompanying photographic illustration.

The design is composed of, first, the light 10 ground centers A, partially surrounded by an ornamental border and ornamented by floral and foliage designs arranged thickly at one side of the center A, and extending in the form of a vine or spray over the other portions of 15 said center; secondly, the light smaller centers

B B, ornamented as shown; and thirdly, the variously-shaped figures surrounding the centers A B, and the floral and foliage ornamentation on said figures.

I claim—

The design for a carpet, substantially as 20 shown and described.

In testimony whereof I have signed my name to this specification, in the presence of two subscribing witnesses, this 28th day of April, 1882. 25

DAVID G. MELVILLE.
